A. T. DAWSON ET AL.
AIMING TUBE ADAPTER FOR QUICK FIRING GUNS.
FILED SEPT. 20, 1922.

UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, LONDON, ENGLAND, A BRITISH COMPANY.

AIMING-TUBE ADAPTER FOR QUICK-FIRING GUNS.

Application filed September 20, 1922. Serial No. 589,333.

To all whom it may concern:

Be it known that we, Sir ARTHUR TREVOR DAWSON, bart., and Sir GEORGE THOMAS BUCKHAM, knight, both subjects of the King 5 of Great Britain, residing at Vickers House, Broadway, Westminster, in the county of London, England, have invented certain new and useful Improvements in or Relating to Aiming-Tube Adapters for Quick-Firing 10 Guns, of which the following is a specification.

This invention relates to ordnance having breech mechanism of the wedge or sliding block type and has for its object to make improved provision for the employment of a 15 small-calibre aiming or practice barrel within the bore of the gun.

According to the present invention the practice barrel is unprovided with its own 20 breech mechanism and firing mechanism and is so constructed and arranged that its cartridge can be wedged into and held in position in the chamber of the tube by the existing breech block of the gun and can be fired 25 by the existing firing mechanism carried by the said breech block; means are also provided for extracting the cartridge case of the practice barrels during the movement of the breech block to its open position.

30 In order that the said invention may be clearly understood and readily carried into effect the same will now be described more fully with reference to the accompanying drawings, in which:

35 Figure 1 is a horizontal longitudinal section of the breech end of a gun provided with an aiming or practice barrel in accordance with our invention, and

40 Figures 2 and 3 are respectively a sectional rear elevation and a sectional plan drawn to a larger scale than Figure 1, the plane of section of Figure 2 being indicated approximately by the line 2, 2 of Figure 3 and the plane of section of Figure 3 being 45 indicated approximately by the line 3, 3 of Figure 2.

45 A represents the breech end of the gun, B represents the sliding breech block which is operated by a crank B' on the actuating shaft B² as is well understood and C represents the aiming or practice barrel.

In the construction shewn the practice barrel C, which has sleeves or collars C', C' for bearing against the surface of the car-

tridge chamber of the gun, is formed at its 55 rear with a flange C² which corresponds substantially with the flange of the cartridge used in the gun and which is also formed with projections C³, C⁴ for co-operating with the walls b, b' of the breech recess of the gun 60 to prevent angular movement of the practice barrel during firing. The cartridge chamber of the practice barrel is so formed that when a cartridge C^x is seated therein its tube will be flush with the rear face of the said 65 flange C² on the practice barrel. The breech block during its closing movement therefore operates upon the small-calibre cartridge C^x of the practice barrel as though it were the full calibre cartridge of the gun, and when 70 the breech block occupies the fully closed position the striker or firing pin lies opposite the percussion cap of the said small-calibre cartridge which is fired by releasing the 75 striker in the usual manner.

For the extraction of the small-calibre cartridge case, a special extractor arm D is provided in place of the lower one of the usual extractor arms of the gun, this special extractor arm having an upward extension D' 80 of sufficient length to enable its end to engage with the flange of the small-calibre cartridge C^x; otherwise this extractor arm is similar to the usual extractor arm and is operated in the ordinary manner by the co-operation of the existing cam surface B^x on the breech block with a toe-piece D^x of the extractor arm D. The other usual extractor arm is replaced by a retaining lever E, E' 85 of bell-crank form, the inner arm E of this lever bearing against the aforesaid projection C³ on the flange C² of the practice barrel C to prevent the latter from falling out of the gun when the breech mechanism is opened with the gun at elevation. The outer 90 arm E' of the said retaining lever has an adjustable screw E² which bears against the breech ring of the gun and by means of which the inner arm E can be forced into contact with the said projection C³. This 95 projection may extend rearwards beyond the face of the aforesaid flange on the practice barrel, but is so arranged as to lie opposite the existing recess provided in the breech block to form the aforesaid cam surface B^x 100 and is therefore out of contact with the breech block. To convert the breech mechanism into a condition for using the practice 105

barrel, it is merely necessary to remove the actuating shaft B^2 and the two usual extractor arms, to substitute the aforesaid special extractor arm D and the aforesaid retaining lever E, E' for the said usual extractor arms, and to then replace the actuating shaft.

What we claim and desire to secure by Letters Patent of the United States is:—

- 1. A small calibre practice barrel for a breech loading gun, comprising a flange on the base of said barrel, said flange having a surface for cooperating with the breech recess of the gun in which said barrel is intended to be used, which cooperation prevents the practice barrel from moving about its axis during firing, and a chamber in said base for the reception of the small calibre cartridge.
- 2. A small calibre practice barrel for a breech loading gun, comprising a flange on the base of said barrel, said flange having surfaces on opposite sides for co-operating with the walls of the breech recess of the gun in which said barrel is intended to be used, which co-operation prevents the practice barrel from moving about its axis during firing, and a chamber in said base for the reception of the small calibre cartridge.
- 3. A small-calibre practice barrel for a breech loading gun, comprising a flange on

the base of said barrel, projections on said flange for co-operating with the walls of the breech recess of the gun in which said barrel is intended to be used and a chamber in said base in which chamber the small-calibre cartridge is adapted to lie with its rear face flush with the rear face of said flang.

4. In breech loading guns intended to receive a small-calibre practice barrel, the combination with the wedge breech block, of a special extractor arm replacing one of the usual extractor arms for the gun cartridge case, said special extractor arm being formed to engage with the cartridge of the small-calibre practice barrel and being operated by the existing cam surface on said breech block.

5. In breech loading guns intended to receive a small-calibre practice barrel, the combination with the wedge breech block, of a special extractor arm replacing one of the usual extractor arms for the gun cartridge case, said special extractor arm being formed to engage with the cartridge of the small-calibre practice barrel and being operated by the existing cam surface on said breech block, and a retaining lever for the practice barrel, said lever replacing the other one of the usual extractor arms for the gun cartridge case.

ARTHUR TREVOR DAWSON.
GEORGE THOMAS BUCKHAM.
